UNITED STATES PATENT OFFICE.

STEWART L. SHARPLESS, OF MILWAUKEE, WISCONSIN.

MULTICOLOR-PRINTING MACHINERY.

Application filed May 29, 1925. Serial No. 33,781.

The present invention relates to multi-color printing machinery and is especially applicable for printing a plurality of colors during a single passage of the material being printed through the printing machine.

In printing machinery of this nature difficulty has been experienced in obtaining true registry between the printing of one color and the printing of another color; and, furthermore, difficulty has been experienced in obtaining true duplication on the material being printed of the printing surface of the printing plates caused, for instance, by shifting between the material being printed and the printing surfaces of the printing plates.

It is the object of the present invention to provide means whereby to remedy these difficulties.

For convenience and clarity the material being printed will be hereinafter referred to as paper, and the printing surface being printed as located on printing plates, although such printing surface may be located on other suitable forms, sheets or parts, the term printing plate hereinafter employed including all such agencies.

It is the object of the present invention further to provide novel means whereby the paper being printed is controlled throughout the printing operation in such manner that it is placed in definite position so that the colors being printed by different printing plates register with each other; and, further, to provide novel means whereby drag on the paper is avoided during the printing operation.

A plurality of rotary impression cylinders is exemplified in this improved printing machine. The paper being printed is printed in one or more colors while located about one of the printing cylinders, and is then transferred to the other impression cylinder for being printed with an additional color or colors. In order that the printing of the different colors, while the paper is located about the different cylinders, shall register with each other, so that corresponding lines of one color will be coincident with corresponding lines of another color, it is essential that the paper shall be exactly placed in definite positions on the respective cylinders. In order to effect such transfer in accurate manner a transfer cylinder is provided, and the transfer cylinder is driven

from the impression cylinders, and the means for rotating the transfer cylinder are further relieved from all heavy duty.

One of the objections in printing machinery as heretofore constructed has been that the impression on the sheet being printed was not a true reproduction of the printing surface of the printing plate, this impression often showing the printing lines and printing dots wider or of greater area than the lines and dots in the printing surface of the printing plate, and the impression further showing cross streaks of heavier printing not found in the printing surface of the printing plate, and other inaccuracies appearing, for which it has been difficult to find explanation.

I have found that in certain characters of printing machines, and in manipulation of printing machines, a pull has been exerted on the sheet during printing, which resulted in a shifting between the paper and the printing surface during the printing operation, resulting in a spreading of the lines on the impression on the sheet, and a consequent darker appearance of the printed subject, and a consequent inaccuracy in reproduction of the printing lines in the printing surface.

I have found that if the paper being printed is transferred from one impression cylinder to the other with accuracy, and the paper is printed with a true rolling contact against the printing surface, that great improvement in printing will be effected, and it is the object of the invention to provide novel means for effecting such improvements.

It is the object of this invention, further, to control the rotation of the transfer cylinder from the impression cylinders; further, to provide means whereby the angular relation of the impression cylinders and transfer cylinder are accurately controlled at the moment of transfer of the sheet being printed from one to the other; further, to provide novel means whereby shifting of the advancing edge of the sheet is avoided during the transfer; further, to provide novel means whereby true rolling contact is obtained between the printing surface and the paper being printed; further to provide novel means whereby the initial point of contact between the printing surface and the paper is controlled; and, further, to provide means whereby such initial points of con-

tact are controlled with relation to each other, and the position of the advancing edge of the paper is controlled with relation to such initial points of printing contact.

5 The invention will be further readily understood from the following description and claims, and from the drawings, in which latter,

Fig. 1 is a side elevation of an exemplifying printing machine embodying my invention, only so much of the printing machine being shown as is necessary to include my invention.

Fig. 2 is a reverse side elevation of the 15 same.

Fig. 3 is a rear elevation of one side of the machine.

Fig. 4 is a cross-section of the same, taken on a line corresponding to the line 4—4 of 20 Fig. 3.

Fig. 5 is a horizontal section of the same, taken on a line corresponding to the line 5—5 of Fig. 2.

Fig. 6 is a detail of one of the gear-segments, taken on the line 6—6 of Fig. 2.

The frame of the machine includes side frame-members 11, 12, suitably connected crosswise of the machine, one of the connections being exemplified as a base plate 30 13, to which the lower ends of the side frame-members are suitably connected, as by bolts.

A pair of impression cylinders are exemplified at 14, 15. The impression cylinder 14 is provided with a shaft 16, to which it 35 is suitably fixed, and the impression cylinder 15 is provided with a shaft 17, to which it is suitably fixed.

The shafts 16 and 17 are rotatable in suitable bearings, suitably adjustable vertically 40 and horizontally in the frame in usual manner for effecting the desired adjustments.

A transfer cylinder 21 is located between the impression cylinders, and is shown provided with a shaft 22, to which it is suitably 45 fixed, and which is journaled in suitable ball-bearings preferably positioned in the frame for forming a fixed axis of rotation for said transfer cylinder.

The shaft 16 has a gear 31 fixed thereto, 50 and the shaft 17 has a gear 32 fixed thereto. The gear 31 comprises a driven portion 33 and a driving portion 34, spaced apart by an annular groove 35, which driven portion and driving portion may be designated a 55 driven gear and a driving gear fixed together.

The gear 32 is exemplified as having a driven portion 36 and a driving portion 37, separated by an annular peripheral groove 60 38, which driven portion and driving portion may be instanced as a driven gear and a driving gear fixed together.

The gears 31, 32, are respectively fixed 65 to the respective shafts of the impression cylinders.

A gear 41 is fixed to the shaft 22 of the transfer cylinder. This gear is an intermediate gear between the driving gears of the impression cylinders, and receives its rotation from said driving gears. The sole 70 duty of said driving gears and said intermediate gear is instanced as the rotation of said transfer cylinder, which is a readily rotatable cylinder, so that said gears while massive have very little duty to perform 75 and consequently maintain their accuracy throughout long use, whereby accuracy of rotative relation between said impression cylinders and said transfer cylinder is maintained.

80 The impression cylinder 14 is provided with bearers 42 at its respective ends. The impression cylinder 15 is provided with bearers 43 at its respective ends. The bearers of the impression cylinders are preferably hardened and ground bearers.

85 The transfer cylinder 21 is provided with end-plates 44 at its respective ends to support the gripper shaft of said transfer cylinder and the operating means therefor. The outer peripheries of the end-plates of the transfer cylinder are preferably out of contact with the bearers of the impression cylinders.

90 The impression cylinder 14 is provided with tympan sheets 46 stretched about the impression receiving sector 47 of said impression cylinder in usual manner. It is also provided with grippers 48 on a gripper shaft 49 suitably operated in usual manner.

95 The impression cylinder 15 is provided with tympan sheets 51 stretched about the impressing sector 52 of said impression cylinder in usual manner. Said impression cylinder is also provided with grippers 53 on a gripper shaft 54 suitably operated in usual manner.

100 The transfer cylinder 21 is provided with grippers 56, on a gripper shaft 57, suitably operated in usual manner. Said transfer cylinder is also provided with a sheet supporting periphery 58, between its end-plates, which is of less diameter than said end-plates for providing spaces 59, 60, between the impression sectors of said impression cylinders and the sheet supporting periphery of said transfer cylinder, in order that when a sheet is gripped by the grippers 56 of the transfer cylinder, the said grippers may not drag said sheet with relation to its position on the sheet supporting sector of the impression cylinder from which it is being received, and to prevent any pulling action upon said sheet while being printed between said impression cylinder and the printing surfaces on the plate cylinders.

105 110 115 120 125 130 This construction also avoids pressure upon the paper between the transfer cylinder and the impression cylinders, and avoids pull upon the paper during the transfer

thereof from the grippers of the transfer cylinder to the grippers of the second impression cylinder, and avoids pull on the paper during the printing while on the second impression cylinder.

Means are provided whereby coacting cylinders are definitely located with relation to each other at the moments of the taking of the sheet by any of the cylinders.

10 In order to control the angular relations between said cylinders at the gripping moment of the grippers, I provide angular positioning means between said cylinders, instanced as a gear-segment 61, which is a portion

15 of the gear of the transfer cylinder, and has its teeth properly cut to full size for initiating proper angular relation between the transfer cylinder and the impression cylinders. The teeth of the driving gears of the

20 impression cylinders, especially those meshing with the gear-segments, are preferably full size and arranged for proper and full meshing with the gear-segments.

The gear-segment 61 is shown mounted 25 in a recess 62 in the periphery of the gear 41, and as provided with a side apron 63, having slots 64 therein, through which clamp bolts 65 are received and threaded into the body of the gear 41, for clamping the gear-segment in proper and adjusted relation to the gear 41.

This gear-segment is in the same angular position on the transfer cylinder as the angular position of the gripping ends of the 30 grippers on said cylinder when in gripping position, so as to locate the transfer cylinder in correct angular relation with the impression cylinders at the moment that the grippers of the transfer cylinder grip the sheet 40 while receiving it from the first impression cylinder or release the sheet while delivering it to the second impression cylinder, the grippers on adjoining cylinders adjoining each other at the moments of gripper transfer.

This angular position of the gear-segment corresponds also with the angular position of the gripping ends of the grippers 53 on the impression cylinder 15 when they coat 50 with the grippers on the transfer cylinder for transferring the sheet being printed from the transfer cylinder to the second impression cylinder 15.

The impression cylinders coact with the 55 printing surfaces from which the printing is effected. These printing surfaces are instanced as on plates, exemplified for instance at 67. The supporting means for the printing surfaces, plates or forms are instanced as cylinders, on which said printing plates or forms are suitably adjustably secured or otherwise maintained.

Four of such plate cylinders are instanced 60 at 71, 72, 73, 74. The plate cylinders are fixed to shafts journaled in suitable bearings

in the frame adjustable vertically and horizontally in suitable manner. Each plate cylinder may be instanced as printing in a different color from the rest.

The plate cylinders 71, 72 are a pair of 70 plate cylinders which coact with the first impression cylinder 14, and the plate cylinders 73, 74 are a pair of cylinders which coact with the second impression cylinder 15 for forming the respective printing couples. 75 The plate cylinders are provided with plate receiving peripheries 75, and with bearers 76 at their respective ends, these bearers being preferably hardened and ground bearers which coact with the bearers on the respective impression cylinders.

The printing plates are provided with printing surfaces and are so positioned on the plate supporting cylindrical intermediate surface of the plate cylinders that their printing surfaces are in a cylinder coincident with the cylinder of said bearers on said respective plate cylinders. The outer cylindrical surfaces of the sheets being printed supported on the tympan sheets on the impression cylinders are located in cylinders which are coincident with the cylinders of the bearers on said impression cylinders. The bearers of the plate cylinders and of the impression cylinders roll upon one another 90 during the printing operation, and, due to such construction and arrangement, produce a true rolling contact between the printing surfaces on the plate cylinders and the paper located on the outer surfaces of the tympan 95 sheets on the impression cylinders.

In order to define the angular relation between the initial edge of the printing surface on the plate cylinder with the location of the advancing edge of the sheet to be printed, I 105 provide each of the gears 81, 82, 83, 84, of the respective plate cylinders with angular positioning means, instanced as a gear-segment 86, similar to the gear segment 61, and similarly adjusted and fixed in place.

The gear-segments preferably have teeth of full and accurate size to correspond with the meshing teeth of the gears on the impression cylinders, the balance of the teeth of the gears of the plate cylinders being preferably reduced in thickness in order that slight play between said gears and the gears on the impression cylinders may be provided, so that, after the angular relation between said respective plate cylinders and the impression cylinder coacting therewith is initiated by the segment-gear, the balance of its rotation will be determined by the frictional rolling contact between the bearers on the plate cylinder and the coacting bearer on the impression cylinder. Meshing of the gears is maintained during tripping of the cylinders.

The angular position of these gear-segments on the plate cylinders corresponds 130

- with the angular position of the gripper ends of the coacting grippers on the complementary impression cylinder, so that the initial printing lines between the printing plate and the paper held by the grippers will be determined by the gear-segment, and the following portion of the printing impression will be determined by the rolling friction contact between the bearers.
- 10 The moments of gripper action on the paper and the moments of initiation of printing by each of the plate cylinders is controlled by the angular positioning means, instanced as the gear segments. The following coactive printing between the printing couples is controlled by the bearer-contacts between the cylinders.
- 15 The same relation of gripper action is obtained by the feeding means for the sheet, effected by a feed cylinder 91. This feed cylinder is fixed to a shaft 92 mounted in suitable bearings in the side frame members of the printing machine, suitably adjusted vertically and horizontally in usual manner.
- 20 25 The shaft 92 has a gear 93 fixed thereon.
- 30 The feed cylinder is provided with end-plates 94 at its respective ends, to support the gripper shaft of said feed cylinder and the operating means therefor. The outer peripheries of said end-plates are preferably out of contact with the bearers of the impression cylinder 14. The feed cylinder is reduced in diameter between said end-plates to support the paper out of pressing contact with the tympan sheets on the first impression cylinder.
- 35 40 This feed cylinder is provided with grippers 95, fixed to a gripper shaft 96, operated in usual and well known manner, for receiving the sheet to be printed from a feed board 97, provided with suitable sheet positioning and releasing guides 89, 90, not more particularly shown or described because well known, for transferring the sheet being fed from the feed board to the feed cylinder by means of gripper action thereon.
- 45 50 The gear 93 of the feed cylinder is provided with angular positioning means, instanced as gear-segments 98, 99, constructed, mounted and adjusted similar to the gear-segments 61, and having teeth which are full-size and arranged to coact with the teeth of the driving gear 34 of the first impression cylinder, in full and proper meshing relation, for defining the true angular positions between said feed cylinder and said impression cylinder at the moments respectively when the grippers on the feed cylinder take the sheet from the feed board and when the grippers on the first impression cylinder take the sheet from the grippers of said feed cylinder. The gear-segment 99 is located in the angular position of the gripping ends of the grippers 95 on the feed cylinder when said grippers are in operative relation, and the
- 55 60 65

gear-segment 98 coacts with the gear of the first impression cylinder at the moment when the gripping ends of the grippers 95 on the feed cylinder take the paper from the feed-board.

70 The driven gear 41 of the transfer cylinder 21 and the driven gear 93 of the feed cylinder 91 preferably have their teeth so cut as to be reduced from normal thickness in order that a slight play or a relative 75 rotation between said cylinders and the impression cylinders is permitted independent of said gears; the said gears, however, maintaining said cylinders in proximate desired relations so that, for instance, suitable tripping mechanism, not shown because well known, may be employed for permitting separation between the impression cylinders and the printing surfaces for reasons which are well known. The gear-segments 80 described, however, define the desired definite relations between said cylinders and between the feed cylinder and the feed board at the moments of sheet taking or sheet transfer for accuracy in printing.

90 After the sheet has been printed, it is delivered from the impression cylinder 15 in suitable manner, as by being received above delivery bars 101 and on to suitable delivery tapes 102, suitably operated for 95 moving the printed sheet away from the printing mechanism without pull upon the sheet which would tend to shift the paper while being printed.

99 100 The driven gears 33, 36, of the impression cylinders are exemplified as driven by an intermediate driving gear 105, located between said driven gears, for exerting its driving forces in opposite directions and thereby balancing its power application. This driving gear is fast with a gear 106 on a sleeve 107, rotatable about a spool 108, on ball bearings 109. The spool is mounted in a bearing 110 in a yoke 11 secured to the side frame member 12, and in a bearing 113 on a bearing-stand 114 extending upwardly from the base and suitably secured to said base. The yoke is received about the driven gear 41 on the transfer cylinder shaft. The parts mentioned are free of connection with 110 the transfer cylinder.

110 115 The bearing spool is clamped in place by means of a rod 115, having nuts 116, 117, at its respective ends, the bearing-spool being provided with collars 118, 119, between shoulders thereon and said bearings 110, 113, whereby the bearing spool and the bearings therefor are relatively positioned.

120 125 A gear 121 meshes with the gear 106, and is mounted on a shaft 122, journaled in bearings 123, 124, respectively in said bearing-stand 114 and a bearing-stand 125, fixed to the base in suitable manner.

130 A pinion 127 meshes with the gear 121, and is fixed to a shaft 128, journaled in a

bearing 129 in said bearing-stand 114 and a bearing 130 of a bearing-stand 131. The shaft 128 is instanced as driven by an electric motor 132, mounted on the base, and 5 having an armature shaft 133. A suitable belt 134 passes about pulleys 135, 136, respectively on the shafts 133, 128, for driving the pinion 127.

All of the gears heretofore described and 10 the pinion are exemplified as provided with helical teeth, the gear-segments being provided with similar teeth.

Suitable inking mechanism is provided, exemplified as comprising inking rollers 141, 142, rotated by suitable mechanism receiving its power from an inker drive shaft 143, such mechanism not being more fully shown or described as the same may be of any 15 desirable character. The inker drive shaft 20 is instanced as driven from the intermediate driving pinion 105, by means of a pinion 144 meshing therewith and having a bevel-gear 145 fast therewith, the gears 144, 145 rotating about a stub-shaft 146 fixed in the 25 side frame-member 12 and a bearing 147 in a bracket 148, fixed to said side frame-member. The bevel-pinion 145 meshes with a bevel-pinion 149 fixed to the inker drive-shaft 143, the latter being journaled in a 30 bearing 150 in said bracket.

By my improved device the feed cylinder and transfer cylinder are devoid of other 35 duty than that respectively of feeding the sheet and transferring the sheet, and the plate cylinders are devoid of other duty than that of rotating and printing.

In the printing operation, the sheet is fed to the feed cylinder and moved by the 40 feed cylinder toward the first or lower impression cylinder. The rotative relation between said cylinders is fixed at the moments of sheet taking and of sheet transfer by the gear-segments on the feed cylinder.

The sheet is fed with the first impression 45 cylinder. At the moment of arrival of its advance edge; that is to say, at the moment of arrival of the grippers on the first impression cylinder at the respective plate cylinders which coact with said first impression 50 cylinder, the correct angular positions of said respective plate cylinders with the gripper positions of the first impression cylinder are fixed, by the momentary engagements between the gear-segments on said respective 55 plate cylinders with the driving gear on said first impression cylinder.

Upon arrival of the grippers of said first impression cylinder at the transfer cylinder, the grippers on the transfer cylinder 60 take the advancing edge of the sheet, whereupon said edge is released by the grippers of the first impression cylinder, which are thereupon moved backwardly and reversely in usual manner, the correct angular relation 65 of such gripper position on the transfer cyl-

inder being fixed by the gear-segments on said transfer cylinder, which also acts to fix the correct angular relation between the grippers on said transfer cylinder and the grippers on the second or upper impression 70 cylinder, upon arrival of the advancing edge of the sheet at the latter gripper position. The grippers on the transfer cylinder thereupon release said sheet, and are moved reversely out of the way in usual manner. 75

The sheet is then advanced past the plate cylinders coacting with the second impression cylinder, the correct angular positions of said respective plate cylinders being fixed by said gear-segments on said plate cylinders just in advance of the moment of the beginning of the printing by said respective plate cylinders. 80

The said plate cylinders coacting with said respective impression cylinders, after such initial angular positions of the same by said gear-segments, are caused to continue their rotations and correct relations with said impression cylinders with which they respectively coact, by the rolling friction contacts between the adjoining bearers on the coacting plate cylinders and impression cylinders. The outer surface of the sheet being printed and the printing surface of the printing plates, being in the cylinders, respectively of the bearers of said impression cylinders and plate cylinders, thus controlled, form true rolling contacts between said printing surfaces and the surface of the sheet being printed, so that true impressions of the printing lines of said printing surfaces are transferred to the sheet being printed. 90 95 100

The outer periphery of the transfer cylinder being spaced from the outer peripheries of the impression cylinders, prevents any pull upon the sheet while being transferred from one impression cylinder to the other, for maintaining accuracy in the position of the advancing edge of the printing sheet, in order to insure and maintain accuracy of registry between the printing lines of the various printing plates on the various plate cylinders. 105 110

The duties of the gearing are divided, the outer train of gearing having the heavier 115 duties of rotating the impression cylinders and driving the inking mechanism and such other mechanism as may be desired on the machine, whereas, the inner train of gearing has the sole lighter duty of rotating the transfer cylinder and the feed cylinder and, with the gear segments, causes registering of the feed cylinder, the transfer cylinder and the plate cylinders, the rotations of the plate cylinders, between the times of action of the gear segments thereon, being caused by the rolling contacts between the bearers of said plate cylinders and impression cylinders, the stress of such latter rotation 120 125 130

being also borne by the outer train of gearing, so that accuracy of registry between the cylinders is maintained.

My improved device therefore provides 5 means whereby accurate printing and accurate registry between printing lines of successive printing surfaces is obtained.

In the present instance the impression cylinders are exemplified as twice the diameter 10 of the balance of the cylinders and as making one-half the number of revolutions as the balance of the cylinders.

Having thus fully described my invention, what I claim as new, and desire to secure by 15 Letters Patent, is:

1. In a multi-color printing machine, the combination of a pair of impression cylinders, a plate cylinder coating with each of said impression cylinders, a transfer cylinder 20 between said impression cylinders, a train of gearing independent of driving connection with said plate cylinders and said transfer cylinder for rotating said impression cylinders, and gearing between said impression cylinders and said plate cylinders and said transfer cylinder for rotating said plate cylinders and said transfer cylinder from said impression cylinders.

2. In a multi-color printing machine, the 30 combination of a pair of impression cylinders, a transfer cylinder therebetween, a pair of plate cylinders for each of said impression cylinders, means for rotating said impression cylinders, a driving gear for each of said impression cylinders, a gear for rotating said transfer cylinder having driven connection with said driving gears, and a driven gear for each of said plate cylinders, said driven gears of said respective pairs of plate cylinders having driven connections with said respective driving gears.

3. In a multi-color printing machine, the 45 combination of a pair of impression cylinders, a transfer cylinder therebetween, a pair of plate cylinders for each of said impression cylinders, means for rotating said impression cylinders, a driving gear for each of said impression cylinders, a gear for rotating said transfer cylinder having driven connection 50 with said driving gears, a driven gear for each of said plate cylinders, said driven gears of said respective pairs of plate cylinders having driven connections with said respective driving gears, grippers on each of said impression cylinders and on said transfer cylinder, angular positioning means between each of said last-named driven gears and said respective driving gears, and angular positioning means between said gear for 55 rotating said transfer cylinder and said respective driving gears, whereby to cause registry between said grippers on said transfer cylinder and said grippers on each of said impression cylinders, and for defining the 60 rotative relations between said cylinders.

4. In a multi-color printing machine, the combination of a pair of impression cylinders, a transfer cylinder therebetween, a pair of plate cylinders for each of said impression cylinders, means for rotating said 70 impression cylinders, a driving gear for each of said impression cylinders, a gear for rotating said transfer cylinder having driven connection with said driving gears, a driven gear for each of said plate cylinders, said driven gears of said respective pairs of plate cylinders having driven connections with said respective driving gears, grippers on each of said impression cylinders and on said transfer cylinder, angular 75 positioning means between each of said last-named driven gears and said respective driving gears, angular positioning means between said gear for rotating said transfer cylinder and said respective driving gears, 80 whereby to cause registry between said grippers on said transfer cylinder and said grippers on each of said impression cylinders, and for defining the rotative relations between said cylinders, and coating friction 85 bearers at the respective ends of said impression cylinders and said plate cylinders effective for defining rotative relations 90 between said impression cylinders and said plate cylinders between coactive relations of 95 said angular positioning means.

5. In a multi-color printing machine, the combination of a pair of superposed impression cylinders, a transfer cylinder therebetween, driving means for said cylinders 100 comprising a gear for each of said impression cylinders embracing a driven portion and a driving portion, a driving gear between the driven portions of said first-named gears for driving said impression 105 cylinders, and a driven gear for said transfer cylinder between said driving portions of said first-named gears.

6. In a multi-color printing machine, the combination of a pair of superposed impression cylinders, a transfer cylinder therebetween, driving means for said cylinders comprising a gear for each of said impression cylinders embracing a driven portion and a driving portion, a driving gear between the driven portions of said first-named gears for driving said impression cylinders, a driven gear for said transfer cylinder between said driving portions of said first-named gears, grippers on each of said cylinders, and angular positioning means between said cylinders causing registry between the grippers of adjoining cylinders.

7. In a multi-color printing machine, the combination of a pair of superposed impression cylinders, a transfer cylinder therebetween, driving means for said cylinders comprising a gear for each of said impression cylinders embracing a driven portion 115 and a driving portion, a driving gear be- 120

tween the driven portions of said first-named gears for driving said impression cylinders, a driven gear for said transfer cylinder between said driving portions of 5 said first-named gears, grippers on each of said cylinders, angular positioning means between said cylinders causing registry between the grippers of adjoining cylinders, and inker driving means having operative 10 connection with said first-named driving gear.

8. In a multi-color printing machine, the combination of a pair of superposed impression cylinders, a pair of superposed plate 15 cylinders coacting with each of said impression cylinders, all said plate cylinders superposed, a transfer cylinder between said superposed impression cylinders, a train of gearing for rotating said impression cylinders, and trains of gearing independent of 20 said first-named train for rotating said transfer cylinder and said plate cylinders from said impression cylinders.

9. In a multi-color printing machine, the combination of a pair of superposed impression cylinders, a pair of superposed plate cylinders coacting with each of said impression cylinders, all said plate cylinders superposed, a transfer cylinder between said 25 superposed impression cylinders, a feed cylinder coacting with one of said impression cylinders, a train of gearing for rotating said impression cylinders, and trains of gearing independent of said first-named 30 train for rotating said feed cylinder, said transfer cylinder and said plate cylinders from said impression cylinders.

10. In a multi-color printing machine, the combination of a pair of superposed impression cylinders, a pair of superposed plate cylinders coacting with each of said impression cylinders, all said plate cylinders superposed, a transfer cylinder between said 35 superposed impression cylinders, a feed cylinder coacting with one of said impression cylinders, a train of gearing for rotating said impression cylinders, trains of gearing independent of said first-named 40 train for rotating said feed cylinder, said transfer cylinder and said plate cylinders from said impression cylinders, and angular 45 positioning means between said impression 50 cylinders and the balance of said cylinders.

11. In a multi-color printing machine, the combination of a pair of impression cylinders, a transfer cylinder therebetween, and a pair of trains of gears, one of said trains of gears comprising an intermediate driving gear and a pair of driven gears, the other of said trains of gears comprising an intermediate driven gear and a pair of driving 55 gears, the gears of said pairs of gears and said impression cylinders respectively having coincident axes of rotation and fixed together, and said intermediate driven gear 60 fixed to said transfer cylinder for rotating the latter.

12. In a multi-color printing machine, the combination of a pair of impression cylinders, a transfer cylinder therebetween, and a pair of trains of gears located side by side, one of said trains of gears comprising an intermediate driving gear and a pair of driven gears, the other of said trains of gears comprising an intermediate driven 65 gear and a pair of driving gears, the gears of said pairs of gears and said impression cylinders respectively having coincident axes of rotation and fixed together, said intermediate driven gear fixed to said transfer 70 cylinder for rotating the latter, and said intermediate gears free to rotatively float with relation to each other.

13. In a multi-color printing machine, the combination of a plurality of impression 75 cylinders, a transfer cylinder therebetween, and an inker driving mechanism, a pair of trains of gears located side by side, one of said trains of gears comprising an intermediate driving gear and a pair of driven gears, the other of said trains of gears comprising an intermediate 80 driven gear and a pair of driving gears, the gears of said pairs of gears and said impression cylinders respectively having coincident axes of rotation and fixed together, said intermediate driven gear fixed to said transfer cylinder for rotating the latter, and said inker driving mechanism having operative connection with said intermediate driving gear for operating the inker mechanism.

In testimony whereof, I have hereunto signed my name.

STEWART L. SHARPLESS.
